UNITED STATES PATENT OFFICE.

LEO J. GRUBMAN, OF BELLE HARBOR, NEW YORK, ASSIGNOR TO VOICES, INCORPORATED, OF NEWARK, NEW JERSEY, A CORPORATION OF DELAWARE.

SOUND-PRODUCING DEVICE.

Original application filed January 12, 1925, Serial No. 1,826. Divided and this application filed April 14, 1926. Serial No. 101,893.

This application is a division of my pending application for Patent Serial No. 1,826, filed January 12, 1925.

This invention relates to sound producing devices or voices, and more particularly to a device of that type wherein air is expelled under the pressure of a gravity movable member through a sounding reed, and in which means is provided for articulating the emission of the sound to simulate the word "ma-ma" or other characteristic cry in accordance with the particular toy figure in which the device is incorporated.

Generically considered, the essential feature of the present improvement resides in the provision of an articulating valve member having a spherical surface adapted during the movement of the air expelling member, to cooperate with the wall of a sound escape opening or passage and check or impede the emission of sound therethrough.

It is another object of the invention to provide a concaved or cupped directing surface leading to the sound escape opening and by which the valve member is directed into cooperative relation with said opening.

With the above and other objects in view, the invention consists in the improved sound producing device or voice, and in the form, construction and relative arrangement of its several parts as will be hereinafter more fully described, illustrated in the accompanying drawings, and subsequently incorporated in the subjoined claims.

In the drawing, wherein I have illustrated one simple and practical embodiment of the device, and in which similar reference characters designate corresponding parts throughout the several views,

Figure 1 is a longitudinal sectional view through a sound producing device illustrating one practical construction thereof;

Fig. 2 is an end elevation with the casing cover removed;

Fig. 3 is a horizontal section taken on the line 3-3 of Fig. 1, and

Fig. 4 is a detail sectional view taken on the line 4-4 of Fig. 1.

For purposes of illustration, I have shown my present improvements as applied to a familiar type of voice device wherein the air receiving and compression chamber is enclosed within a suitable housing or casing. This casing may be of cylindrical or other

desired form and is most conveniently and inexpensively produced from a section of cardboard tubing constituting the body wall 5, the opposite ends of which are adapted to be closed by the metal heads 6 and 7 respectively. In the present instance, the compression chamber is in the form of a collapsible bellows having a flexible cylindrical body wall 8 suitably fixed at one of its ends to one end of the casing wall 5 and having its other end edge suitably attached to a weighty air compressing and expelling member generally indicated at 9. One wall of the outer casing, preferably the closure head 7 thereof is provided with a plurality of suitably arranged sound emission openings 10 therein.

As herein shown, the bellows head 9 is in the form of a disc having an annular flange 11 at its outer edge providing a recess as at 12 in one side of said disc, which receives one end edge of the flexible bellows wall. A sheet metal plate 13 closes the open side of this recess and is provided at its periphery with a reversely bent flange 14 adapted to fit within the end of the cylindrical bellows wall and tightly clamp the edge thereof against the angular surfaces of the recess 12. This metal plate 13 at one side of its center is suitably stamped to provide a rigid channel 15 open at one of its ends and at the inner side thereof opposed to the bellows chamber. A vibratory sound producing element 16 is fixed to said plate and positioned over this inner open end of said channel. The space between the plate 13 and the body wall of the member 9 provides a sound receiving chamber 17. The member 9 is centrally formed with a short boss 18 against the end edge of which the plate 13 is engaged, said boss being provided with one or more sound passages 19. The member 9 is further provided centrally thereof with a relatively long extension 20 projecting from its opposite side, the end of said extension being reduced in diameter and having suitably fixed thereon a disc 21 provided with a plurality of apertures 22 therein. The boss 18 and extension 20 are provided with an axially extending bore 23, said bore at the end of the extension 20 having a tapering or contracted section 24 connected with a cylindrically reduced section 25. The sound emission orifice 26 communicates with the outer end of the bore section 25.

100

105

Within the inner end of the bore 23 and in spaced relation to the plate 13, a plug 27 is snugly fitted, said plug having a central opening 27' therethrough tapering or flared at its opposite ends as at 28 to the periphery of said plug. These tapered or flared ends of the plug provide concave or cup shaped directing surfaces leading to the sound escape opening or passage 27' of said plug. Between this plug and the reduced end of the bore 23 a cruciform member 29 is arranged, the outer edges of the webs or flanges of said member having snug frictional contact with the wall of said bore. The upper and lower edges of these webs or flanges are reversely inclined as at 30 so that said webs gradually decrease in width from the inner ends to the outer ends thereof. A free gravity movable valve member 31 is arranged within the bore 23 and controls the volume of the sound emitted through the orifice 26. This member, as herein shown, is preferably in the form of a ball having a spherical surface of such diameter that it may pass between the flanges or webs of the member 29 and also through the opening 27' in the member 27 but cannot move through the passages 19 or through the orifice 26.

In the operation of the device as above described, when it is arranged in one position to cause the expansion of the bellows and the inflation of the air chamber, the valve member 31 is seated over the inner end of the orifice 26 and closes the same, except when it may be momentarily displaced by the ingress of air therethrough to the bellows chamber. When the device is reversed to the position shown in Fig. 1, the gravity descent of the member 9 expels air under pressure through the sounding reed and the valve member 31 at the same time moves downwardly by gravity. It will be noted that the section 25 of the bore or passage is of such diameter relative to the valve ball that sound may escape in restricted volume past said ball and through the orifice 26 to simulate the initial letter "m" of the syllable "ma". After the ball leaves the section 25 of said passage it strikes upon the upper end of the cruciform member 29 and drops downwardly between the spaced webs or flanges thereof. In this movement of the ball the sound may pass in greater volume through said passage and the orifice 26 to simulate the sound of the letter "a" which completes the first syllable, "ma". In the continued downward movement of the ball, it is directed by one of the concaved surfaces 28 to the sound opening or passage 27'. The expulsion of air under pressure from the bellows chamber through this small diameter passage acting upon the ball, to a certain extent overcomes the action of gravity and retards its downward movement

through said passage. During this part of the movement of the valve ball, sound again escapes in relatively restricted volume between the spherical surface of the ball and the wall of the passage 27' and is finally emitted through the orifice 26 to again simulate the sound of the letter "m". When the ball falls through the passage 28 and reaches a position of rest on the plate 13, sound may then pass in maximum volume from the chamber 16 through passages 19 and passage 27' to the orifice 26, again sounding the letter "a" and completing the simulation of the second syllable "ma". It will be understood of course, that in the construction of such a device, the weight of the member 9 and parts connected therewith is accurately determined with relation to the weight of the valve ball 31 so that the pressure of the expelled volume of air and its retarding effect upon the gravity movement of the ball in addition to the members 27 and 29 which also interrupt and retard such movement, will produce the desired time relation between the simulated articulation of the word syllables. In the descent of the member 9, air within the casing exterior of the bellows chamber, may pass freely through the openings 22 of the disc 21 to avoid any cushioning effect by said disc and to cooperate with the wall of the housing or casing and prevent any substantial lateral tilting of the member 9.

From the foregoing description considered in connection with the accompanying drawings, the construction, and manner of operation of the herein described embodiment of my present improvements will be clearly understood. It will be seen that I have provided an improvement of fundamental character in devices of this character in that the sound emission controlling valve member has a spherical surface and means is provided for directing and positioning such a valve member with respect to a sound emission opening or passage through which the sound waves are expelled under pressure and against the spherical surface of said valve member. By providing the valve member with such a spherical surface, the counteracting pressure upon said valve member tending to displace the same relative to the wall of the sound escape opening or passage is equally distributed, and the emission of the sound past said valve member will therefore, be substantially uniform during the operation of the device. I have herein disclosed a physical embodiment of the essential feature of the present improvements which may be readily produced in commercial form, but it is contemplated that similar results might also be obtained in various other alternative structures. Accordingly, it is to be understood that I do not desire to be limited to the specific construction

herein disclosed, but reserve the privilege of adopting all such legitimate modifications thereof as may be fairly incorporated within the spirit and scope of the invention as 5 claimed.

I claim:

1. In a sound producing device, a sounding reed, a movable member having a passage in communication with the reed at one 10 of its ends and having a sound outlet at its other end, said member upon movement in one direction causing a flow of air through said reed and the passage, a valve member movable through said passage, and said 15 member being provided with relatively fixed means at one end of said passage for directing said valve member from a non-obstructing position into cooperative relation with a wall of said passage to impede the emission 20 of the sound therethrough.
2. In a sound producing device, a sounding reed, a movable member having a sound emission passage in communication with the reed at one of its ends, said member upon 25 movement in one direction causing a flow of air through said reed and the passage, a valve member carried by said movable member and having uninterrupted movement relative to the latter during the operative 30 movement thereof into cooperative relation with said sound emission passage to impede the emission of sound therethrough, and additional means carried by said movable member for directing the valve member from a 35 non-obstructing position into such cooperative emission impeding relation to said passage.
3. In a sound producing device, an air chamber having an outlet passage, a sound 40 producing reed, a weighty gravity movable member for expelling air under pressure from said chamber through the reed and said passage, said member having a part

provided with an opening in communication with said passage and a concaved directing 45 surface leading to said opening, and means for articulating the emission of sound through said passage comprising a valve member having a convex surface to engage upon and be directed by said concave surface into cooperative relation with said opening to impede the passage of sound therethrough.

4. In a sound producing device, an air chamber having an outlet passage, a sound 50 producing reed and means for expelling air under pressure from said chamber through the reed and said outlet passage, and means for articulating the emission of the sound comprising a valve member movable by 55 gravity in said passage independently of the air expelling means, and means arranged in said passage with which said valve member cooperates whereby gravity movement of said member is retarded and the emission of 60 the sound restricted at spaced intervals in the operation of the air expelling means.

5. In a sound producing device, an air chamber and a weighty gravity movable 65 member for expelling air from said chamber, said member having an air outlet passage, a sound producing reed through which the air is expelled from said chamber through said passage, and means for articulating the sound comprising a valve member 70 movable by gravity in said passage independently of the air expelling member, and spaced means in said passage for retarding the gravity movement of the valve member, one of said means cooperating 75 with the valve member to restrict the egress of sound through said passage.

In testimony that I claim the foregoing as my invention, I have signed my name hereto.

LEO J. GRUBMAN.
